CLAIM

The ornamental design for a lid for drinking container, as shown and described.

DESCRIPTION

FIG. 1 is a perspective view of a first embodiment of the lid for drinking container;

FIG. 2 is a front view of the first embodiment of the lid for drinking container;

FIG. 3 is a rear view of the first embodiment of the lid for drinking container;

FIG. 4 is a right side view of the first embodiment of the lid for drinking container;

FIG. 5 is a left side view of the first embodiment of the lid for drinking container;

FIG. 6 is a top view of the first embodiment of the lid for drinking container;

FIG. 7 is a bottom view of the first embodiment of the lid for drinking container;

FIG. 8 is a perspective view of a second embodiment of the lid for drinking container;

FIG. 9 is a front view of the second embodiment of the lid for drinking container;

FIG. 10 is a rear view of the second embodiment of the lid for drinking container;

FIG. 11 is a right side view of the second embodiment of the lid for drinking container;

FIG. 12 is a left side view of the second embodiment of the lid for drinking container;

FIG. 13 is a top view of the second embodiment of the lid for drinking container; and,

FIG. 14 is a bottom view of the second embodiment of the lid for drinking container.

The evenly broken lines are shown for the purpose of illustrating parts of the lid for drinking container that form no part of the claimed design. The dot-dash broken lines,

(Continued)

shown in FIGS. 7 and 14, represent the boundaries of the claim and form no part thereof.
